UNITED STATES PATENT OFFICE.

EMIL TINNERHOLM, OF CHICAGO, ILLINOIS.

WHIPPING-TOP.

No. 806,212.

Specification of Letters Patent.

Patented Dec. 5, 1905.

Application filed February 25, 1905. Serial No. 247,289.

To all whom it may concern:

Be it known that I, EMIL TINNERHOLM, a citizen of the United States, residing at 927 Sheffield avenue, in the city of Chicago, in the county of Cook and State of Illinois, have invented a new and useful Improvement in Whipping-Tops, of which the following is a specification.

The object of my improvement is to provide a whipping-top suitable for the use and amusement of adults as well as young persons and children, that can be used in or out of doors on the ice in winter as well as on the ground or other substance in the summer, that can be used by one or more persons at the same time, that can be set spinning with one or both hands, that when started can be kept in motion by a whip held by a person standing erect, that is so constructed that if the whip-lash strikes any part of the head it will wind around and take firm hold of the neck, that when struck can be made to jump in any direction and be thereby used as a means of a number of games played under prescribed rules by one or more persons as a means of healthful exercise and excitement, and that can be artistically made and cheaply produced.

The manner in which I accomplish my object is described in the following specification and illustrated in the accompanying drawings, in which—

Figure 1 is a complete view of the top, whip, and whip-stock in position ready for spinning with the right hand. Fig. 2 is a central vertical section of the top through the line 2 2, Fig. 3, showing the construction and arrangement of the parts. Fig. 3 is a top view of the top.

The top A is composed of two parts and a ring or collar. The head B is of greater diameter and weight than the body and is designed to serve as a balance-wheel, as a guide for the lash of the whip, and a convenient hold for the hand in winding and spinning.

The under side of this head is in the form of a curve C descending from its largest diameter D to the point E, where it joins the neck.

From the point E of the curve C the bottom of the head is flat. From the point D of the curve C to the point D' is a rim D'. Extending from the point D' to the hole F, which extends through the head, is a depression G, which rises slightly to the point H. This depression and the rim affords a firm hold for the thumb when held ready for spinning.

The lower part I of the top has a blunt point

J, protected by a metallic cap K, which is permanently attached by the shank L. Above the cap the shape of the part I is that of an inverted cone M, provided at the top with a bead N, which forms the largest diameter of the part I. From this bead the diameter decreases to form the neck O, which is adapted in size and shape at the top P to fit the straight part E E on the head B. Extending from the center of this neck is a head-pin Q, adapted in size to fit tightly into the hole F in the head B and to extend clear through it and having a rounded top R projecting slightly above the part H of the depression G. Around the neck O is a collar O', made preferably of rubber and adapted to receive the windage of the whip-lash and prevent slipping when the turns of the lash are few or not quite tight.

When constructed as described and shown and the parts put together permanently and ready for use, the whip-stock S and lash T are held in the right hand, and the end U of the lash is placed, as shown, on the part I of the top and the lash wound around the neck. The thumb lies in the depression G, pressed against the bead D', the fingers grasping the head D and whip-stock S. The top is then thrown in any direction with the point J down, the rapid unwinding of the whip-lash revolving the top rapidly. The point J strikes the floor, carpet, ground, or ice without penetration, and the shape of the point prevents it from penetrating and offers little resistance while in motion. To maintain the motion of the top, it is struck with the lash of the whip, which if it strikes anywhere between the point D of the head B and the point N on the part I will encircle the neck and connect with the collar O'. The angle at which the lash strikes the curve C on the head B causes the top to jump in a direction in height and distance regulated by the will and skill of the players. The top can be set spinning with either hand and by one or both hands and by the whip-lash similar to the one illustrated or by a string and a button, like the ordinary tops.

I am aware that whipping-tops have been made with vertical sides above the cone and with grooves and fillets to guide and hold the lash; but in all these forms of construction the stroke of the whip must be given with the body bent over and the whip-hand held near to the ground, and if the stroke is not delivered very carefully the blow of the lash knocks the top over.

What I claim, and desire to secure by Letters Patent, is—

1. In a whipping-top of the kind described the combination of a head, B, having a central hole, F, and a depression, G, on the top, and a rim, D', and a curve, C; with a body part, I, having a head-pin, Q, adapted to fit and to be held in the hole, F, in the head, B, said part, I, having a point, J, and a cap, K, 10 said cap being secured by a shank, L, said body part being of a conical form and having a bead, N, and a neck, O, and a collar, O', secured on said neck; said parts, B and I, being permanently joined together substantially as 15 described and for the purposes specified.
2. In a whipping-top of the kind described the combination of a body part, I, conical in

form and having a metallic cap, K, a neck, O, and a head-pin, Q, with a head, B, having a curved part, C, and a hole, F, adapted to receive 20 the head-pin, Q, of the body part, I, and a collar, O', secured on said neck, said head, B, and body part, I, being permanently joined together substantially as described and for the 25 purposes specified.

3. A top of the kind described having a head B with flat depression G therein, a rim D', curve part C, neck O, bead N, and conical part M, substantially as described and for the purposes specified.
